CLAIM

We claim the ornamental design for a uterine contraction timer, as shown and described.

DESCRIPTION

FIG. 1 is a perspective view of the uterine contraction timer;
FIG. 2 is a frontal elevational view thereof;
FIG. 3 is a right side elevational view thereof;
FIG. 4 is a rear elevational view thereof;
FIG. 5 is a left side elevational view thereof;
FIG. 6 is a bottom plan view thereof; and,
FIG. 7 is a top plan view thereof.
